CLAIM

The ornamental design for a pharmaceutical dispensing device, as shown and described.

DESCRIPTION

FIG. 1 is a side elevational view of the pharmaceutical dispensing device design showing the base of the dispenser with the cap placed thereon;

FIG. 2 is a top plan view of FIG. 1;

FIG. 3 is a bottom plan view of FIG. 1;

FIG. 4 is a perspective view of FIG. 1;

FIG. 5 is a side elevational view shown with the cap portion removed to disclose the underlying parts;

FIG. 6 is a side elevational view of the cap portion, shown separately for clarity;

FIG. 7 is a front elevational view of FIG. 5;

FIG. 8 is a front elevational view of FIG. 6;

FIG. 9 is a front perspective view of FIG. 5; and

FIG. 10 is a front perspective view of FIG. 6.

FIG. 11 is a side elevational view of the pharmaceutical dispensing device design showing the base of the dispenser with the cap placed thereon;

FIG. 12 is a top plan view of FIG. 11;

FIG. 13 is a bottom plan view of FIG. 11;

FIG. 14 is a perspective view of FIG. 11;

FIG. 15 is a side elevational view shown with the cap portion removed to disclose the underlying parts;

FIG. 16 is a side elevational view of the cap portion, shown separately for clarity;

FIG. 17 is a front elevational view of FIG. 15;

FIG. 18 is a front elevational view of FIG. 16;

FIG. 19 is a front perspective view of FIG. 15; and,

FIG. 20 is a front perspective view of FIG. 16.

The broken lines shown in FIGS. 11-16, 19 and 20 are included for the purpose of illustrating portions of the pharmaceutical dispensing device that form no part of the claim to the second embodiment.
